UNITED STATES PATENT OFFICE

ERNEST HAMWI, OF ST. LOUIS, MISSOURI

DESIGN FOR AN ICE-CREAM CONE

Application filed August 12, 1929. Serial No. 32,386. Term of patent 14 years.

To all whom it may concern:

Be it known that I, ERNEST HAMWI, a citizen of the United States, residing at the city of St. Louis and State of Missouri, have invented a new, original, and ornamental Design for Ice-Cream Cones, substantially as shown in the accompanying drawing, in which—

Fig. 1 is a side elevation of an ice cream cone showing the new design.

Fig. 2 is an upper end elevation of the cone.

I claim:

The ornamental design for an ice cream cone, substantially as shown.

ERNEST HAMWI.
